UNITED STATES PATENT OFFICE.

MONTGOMERY LONG, OF SPARTANBURG, SOUTH CAROLINA, ASSIGNOR TO
O. P. MORGAN AND L. W. OSBORNE, OF SAME PLACE.

HYDRAULIC FORCE-PUMP.

SPECIFICATION forming part of Letters Patent No. 476,898, dated June 7, 1892.

Application filed July 9, 1891. Serial No. 398,875. (No model.)

To all whom it may concern:

Be it known that I, MONTGOMERY LONG, a citizen of the United States, residing at Spartanburg, in the county of Spartanburg, State 5 of South Carolina, have invented certain new and useful Improvements in Hydraulic Force-Pumps, of which the following is a specification, reference being had therein to the accompanying drawings.

10 This invention relates to certain new and useful improvements in hydraulic force-pumps for elevating water, used as a power-lift, operating ropeways, and other purposes.

It has for its objects, among others, to provide a simple, cheap, durable, and efficient pump of this character having provisions for increasing or diminishing the leverage at will to conform to the water-supply, which from natural sources is always a variable quantity, 20 and the owner is thus enabled to utilize such supply to the best advantage and not diminish the duty of the pump.

Other objects and advantages of the invention will hereinafter appear, and the novel 25 features thereof will be specifically defined by the appended claims.

The invention is clearly illustrated in the accompanying drawings, which, with the letters of reference marked thereon, form a part 30 of this specification, and in which—

Figure 1 is a front elevation with portions in section and parts broken away, showing my improved pump. Fig. 2 is a side elevation of the same with parts in section and portions 35 broken away.

Like letters of reference indicate like parts in both of the views.

Referring now to the details of the drawings by letter, A designates a suitable framing for the pump-house A', and rising therefrom is the upright A², at the upper end of which is supported the cross-head A³ in any suitable manner. Suitably journaled on shafts B' in this cross-head are the grooved pulleys 40 B, over which the chains or cords B² are supported, as shown. These chains or ropes are attached at one end to a receiver C and at their other ends are attached to the levers D, which are arranged with their upper ends ex- 45 tended substantially horizontally, as seen best in Fig. 1. These levers can be connected with

the chains or ropes in any suitable manner, a simple hook a being shown in the present instance. These levers are provided with a plurality of notches or analogous provisions a' 55 to provide for adjustment of the connections which support the receivers E, which are supported therefrom, as seen in Fig. 1, and suitable means of support being employed, so that the leverage may be easily and quickly 60 changed when desired. These receivers are provided with valved openings in their bottoms, as seen in Fig. 1, and these openings are controlled by the valves b, which are normally held to their seats by springs b', as seen in said 65 view, the valves being connected with the cords or chains b², which are attached to the levers, as seen in Fig. 1.

The receiver C has in its bottom valve-controlled openings c, the valves c' being suitably 70 hinged, as seen in Fig. 1, and acted upon by the springs c² to normally hold them to their seats, pins d being provided at the top of the pump-house, with which these valves contact as the receiver C reaches its lowest point of 75 descent, as seen in Fig. 1, and the valves thus opened.

F are chains or cords connected to the receiver C and to the pump-house, as shown, and for a purpose hereinafter explained. 80

G is the pump-barrel within the pump-house and provided with a valve g at its lower end and near its upper end with the discharge-pipe g', as seen best in Fig. 2.

H is the piston working in the pump-barrel 85 and provided with two lip-valves h, which open and receive the water as the piston or plunger descends and close as it ascends.

I is the piston-rod working through an opening in the top of the pump-barrel and provided with a double-racked bar I', as shown 90 in both views, and with which engage the teeth of the mutilated pinions I², which are journaled upon suitable shafts i on the upright A² and to which the lower ends of the levers 95 D are connected eccentrically, as seen in Fig. 1.

K is the supply-gate or head-water.

With the parts arranged as above described, and as shown in the drawings, the operation is as follows: The receivers E, which may 100 be of any convenient capacity commensurate with the water-supply or the duty demanded

or power required, receive their momentum and power from the supply K, of which there are two, one over each receiver, and when the receivers are full or partially full of water 5 they fall a certain prescribed distance, actuating through the lever-arms and their connection with the pinions the rack and piston and the plunger of the pump, forcing the same upward and discharging the water from the 10 pump through the outlet g'. As the receivers E make their downward stroke they carry up by means of the chains or cords the receiver C to the same height and under the supply K, which now discharges into the said receiver 15 C, and when it is full or partially full causes it to fall, reversing the position of the receivers E E and the pump-plunger, when the supply 20 discharges into the receivers E E and the operation is repeated. The valves in the receivers E are lifted from their seats by the cords b² near the limit of the downstroke, while, 25 vice versa, the valve-lifting pins in the top of the pump-house raise the valves in the receiver C as it comes to rest thereupon. The stroke-regulator chains or cords F limit the downward stroke of the receivers E E by prescribing the distance through which they may fall equal to the throw of the pump-plunger.

Various modifications in detail may be 30 sorted to without departing from the spirit of

the invention or sacrificing any of its advantages.

What I claim as new is—

1. The combination, with a force-pump, of the piston-rod of said pump, having rack portion, the pinions, the levers connected with the pinions, the receivers carried by the levers, the counterbalance-receiver connected with the receivers, and means for adjusting the leverage, as set forth. 40

2. The combination, with the piston-rod having rack, of the pinions meshing therewith, the levers connected with the pinions, the receivers adjustable on the levers, the counterbalance-receiver, and the cords connecting the 45 levers and counterbalance - receiver, as set forth.

3. The combination, with the force-pump, the racked piston-rod thereof, the pinions, and the levers connected therewith, of the receivers, the counterbalance-receiver, the valves and their operating means, and the stroke-regulating cords, all substantially as and for 50 the purpose specified.

In testimony whereof I affix my signature in 55 presence of two witnesses.

MONTGOMERY LONG.
